United States Patent Office

Des. 211,499
Patented June 18, 1968

211,499

POWERED WATERCRAFT

Walter E. Hofius, 4030 W. 108th St.,
Bloomington, Minn. 55431

Filed June 9, 1967, Ser. No. 7,411

Term of patent 14 years

(Cl. D71—1)

FIGURE 1 is a perspective view of the front of the powered watercraft showing my new design;

FIGURE 2 is a left side elevation view;

FIGURE 3 is a top plan view;

FIGURE 4 is a front elevational view; and

FIGURE 5 is a rear elevation.

I claim:

The ornamental design for a powered watercraft, substantially as shown.
